CLAIM

The ornamental design for a mechanical camera body (Dmax), as shown and described.

DESCRIPTION

FIG. 1 is a front elevational view of a mechanical camera body (Dmax) showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top-front perspective view thereof, wherein the camera lens shutter is fully open;

FIG. 8 is a top-front perspective view thereof, wherein the camera lens shutter is partially closed and the front lens panel is shown slid down; and,

FIG. 9 is a top-front perspective view thereof, wherein the camera lens shutter is fully closed and the rear panel is shown slid to the right.

The broken lines shown in the drawings illustrate portions of the mechanical camera body (Dmax) that forms no part of claimed design.
